UNITED STATES PATENT OFFICE.

EDWIN L. PRICKETT, OF MOUNT HOLLY, NEW JERSEY.

DESIGN FOR A WATCH-FOB.

SPECIFICATION forming part of Design No. 27,319, dated July 13, 1897.

Application filed May 16, 1897. Serial No. 636,796. Term of patent 3½ years.

To all whom it may concern:

Be it known that I, EDWIN L. PRICKETT, a citizen of the United States, residing at Mount Holly, in the county of Burlington and State 5 of New Jersey, have invented a new and original Design for a Watch-Fob, of which the following is a specification.

This invention relates to a new and original design for a watch-fob; and it has for its object to provide a design of this character that shall be both useful and ornamental.

The leading feature of the design resides in a watch-fob having a flat oblong body-piece provided with an alined longitudinal series 15 of openings, a series of folded links provided with rounded side portions with openings therein and successively looped through each other and the openings in the body-piece, and a separate flat plate pendent from the lowermost link.

A minor feature of the design resides in providing the flat oblong body-piece with rounded ends and in having a strap-loop connected with the upper end of the body-piece 25 and the uppermost folded link.

In the drawings, Figure 1 is a perspective view of a watch-fob embodying the herein-described design. Fig. 2 is a plan view of the reverse side of the fob. Fig. 3 is a central 30 longitudinal sectional view thereof.

Referring to the drawings, the numeral 1 designates a flat oblong body-piece provided with rounded ends 2 and an alined longitudinal series of openings 3. The body-piece 1 has interlaced therein the folded links 4, 35 which are provided with rounded side portions having circular openings 5 therein, and which folded links are successively looped through each other and the openings in the body-piece to provide a duplicate design at 40 each side of the body-piece. A separate flat oblong figure or plate 6 is hung from the lowermost link 4 and is illustrated as being provided with surface ornamentation and rounded ends 7.

The design is completed by connecting a strap-loop 8 with the upper end of the body-piece 1 and the uppermost link 4.

What I claim is—

The design for a watch-fob herein shown 50 and described.

In testimony that I claim the foregoing as my own I have hereto affixed my signature in the presence of two witnesses.

EDWIN L. PRICKETT.
